ELECTRICAL CONDENSER

Frank W. Godsey, Jr., North Adams, Mass., assignor to Sprague Specialties Co., North Adams, Mass., a corporation of Massachusetts

Application July 3, 1940, Serial No. 343,871

6 Claims. (Cl. 175—41.5)

The present invention relates to electrical condensers and more particularly to fixed and adjustable condensers particularly adapted for use as "padder" and tuning condensers in radio receivers.

To be suitable for such use, condensers must meet several important requirements. For example, they must combine a high capacity value with a small volume, must be of rugged construction to withstand wear and vibrations, and be adapted for low cost, mass production. Furthermore, they must be stable, i. e. maintain their adjusted capacity setting even if the condenser is subjected to a wide-range heat cycle.

It is therefore an object of my invention to provide an adjustable condenser which meets all of the above requirements, and which is very small for a given capacity value, is of rugged construction, inexpensive to produce, and exhibits a very high degree of electrical and mechanical stability.

To counteract the changes of the electrical constants of the components of the tuned circuits and particularly the changes in the constants of the tuning coil of such circuits brought about by the wide-range temperature variations encountered in the operation of a radio receiver, and the ensuing changes in the resonant frequency of such circuits, so-called compensating condensers are used in these tuned circuits whereby as a rule one compensating condenser is needed for each tuned circuit.

Such use of individual compensating condensers for each tuned circuit has several disadvantages, chief among which are the high cost and increased complexity of assembly. Because of this, there have been endeavors to provide condensers which do not require separate compensating condensers but serve simultaneously both as tuning condensers and as compensating condensers. Such prior attempts, however, have been unsuccessful because of the erratic and unpredictable compensating characteristics of such prior condensers.

It is therefore a further object of my invention to provide a novel condenser capable of serving both as a tuning and as a compensating condenser of a tuned circuit, and which obviates the difficulties of prior condensers of this type.

These and further objects of my invention will appear as the specification progresses.

The invention will be described with reference to the appended drawing forming part of the specification and in which:

Figure 1 is a partly sectionized side view of an 55 a flat rectangular strip portion 13, which extends

adjustable condenser made in accordance with the invention.

Fig. 2 is a sectional view taken along the line 2—2 of Fig. 1, also showing the mounting means 5 of the condenser, which are not shown in Fig. 1.

Fig. 3 is a side view of a second embodiment of the invention.

Fig. 4 is an end view of the condenser of Fig. 3.

Fig. 5 is a side view of a dual unit condenser 10 made in accordance with the invention.

Fig. 6 is a side view of a condenser in accordance with the invention for the simultaneous tuning and compensating of a tuned circuit.

Fig. 7 illustrates another embodiment of a combined tuning and compensating condenser made in accordance with the invention.

Referring to Figs. 1 and 2, the condenser there shown comprises two concentrically disposed electrodes 10 and 11. Electrode 10 consists of a metal cylinder or preferably a hollow sleeve closed at one end, whereas electrode 11 consists of the effective portions of a wrap-around metal clamp encircling the electrode 10 and to be more fully described later. Interposed between electrodes 20 10 and 11 is a concentric dielectric layer 12 forming an integral coating on the surface of electrode 10. The dielectric layer 12 consists preferably of a potassium lead silicate vitreous enamel, as disclosed in the copending application of Stanley O. Dorst, Ser. No. 289,292 filed August 9, 1939, now U. S. Patent No. 2,290,947 issued July 28, 1942, which is cataphoretically applied to the electrode 10. The layer 12 may also consist of other suitable dielectric materials, for example, 25 30 35 40 various kinds of vitreous enamels, or may consist of a non-vitreous dielectric material such as of cellulose acetate, polystyrene, hard rubber or the like, to which dielectric materials may be added a filler of titanium dioxide or other dielectric material to increase the dielectric constant and/or lower the power factor.

The layer 12 is applied to the electrode 10 preferably by the cataphoretic deposition process described in the copending application of Preston 45 Robinson et al., Ser. No. 197,692 filed March 23, 1938, which produces a coating of high uniformity and of even thickness throughout the length of the coating. As a rule I prefer to also fuse the so-deposited coating and to subject it thereafter 50 to surface grinding as described in the copending application of Robert C. Sprague and Frank W. Godsey, Jr., Ser. No. 336,822, filed May 23, 1940.

The offset wrap-around metal clamp, comprises 55 a flat rectangular strip portion 13, which extends

into two integral and substantially annular segmented outer sleeve portions 14-14, and a similar but wider middle portion 15. The portions 14-14 and 15 surround the coated electrode 10 and form the complementary electrode thereto.

The sleeves 14-14 and 15 extend into rectangular flaps 16-16 and 17 respectively, bent parallel with and disposed adjacent to the strip 13. The flaps 16-16 are each fixedly secured to the strip 13 by rivets 18-18 or similar fastening means, to press the sleeves 14-14 with a high and constant pressure against the dielectric layer 12 underlying same.

The flap 17 is adjustably secured to the strip 13 by means of a bolt 19 which passes through a corresponding hole 20 of the strip 13 and threadingly engages the flap 17.

The condenser is mounted on a base, for example, as shown in Fig. 2, on the metal chassis 22 of the radio receiver, by means of rivets or bolts 23-23 engaging holes 21-21 of strip 13.

The capacity of the condenser is adjusted by means of the bolt 19 which depending on its adjustment causes the segment 15 to exert a greater or lesser pressure on the dielectric layer 12, resulting in the formation of an air-gap of smaller or larger thickness between the segment 15 and the layer 12. For the convenient adjustment of the bolt from either side of the condenser, both the head and the end of the bolt are preferably slotted, and the chassis 22 is cut out at 27, to permit passage of and access to the head of bolt 19.

Outside electrical connection to the electrode 11 is provided as a rule by the metal chassis itself. If a nonconducting mounting base is used, a terminal lug 24 is provided which can be secured to the strip 13 by the rivet 23. Electrical connection to the electrode 10 is provided by a terminal lug 25, secured to the uncoated end-face of the electrode 10, for example, by means of a rivet 26.

The condenser shown in Figs. 3 and 4 comprises an inner cylindrical electrode 50 consisting of a preferably hollow, metal cylinder or sleeve and a dielectric layer 51 preferably of a vitreous dielectric material applied to the electrode 50 as an integral coating thereon. The electrode 50 and the dielectric layer 51 conform to the requirements stated for the corresponding elements 10 and 12 of the condenser of Figs. 1 and 2.

The outer and adjustable electrode of the condenser consists of an undivided substantially cylindrical or sleeve portion 54 of a wrap-around metal clamp 52 and surrounds the electrode 50. The sleeve 54 extends into a longer flap 53 and a shorter flap 55, the two being bent radially in parallelism along the length of the shorter flap.

Whereas to facilitate the mounting of the condenser of Figs. 1 and 2, the wrap-around clamp member 11 is formed with an offset portion, whereby the flaps extend tangentially to the sleeve electrodes, in practice as a rule I prefer to use the construction shown in Figs. 3 and 4, in which the flaps of the sleeve extend radially, and the sleeve electrode is in direct contact with the dielectric layer throughout its major area.

The flaps 53 and 55 are pivoted and held together at one end of their opposing faces by means of a rivet 58, whereas at the other end they are adjustably clamped together by means of a bolt 59. The bolt 59 passes through a cor-

responding hole of the flap 53 and threadedly engages a threaded bore of flap 55.

The capacity of the condenser is adjusted by tightening or loosening the bolt 59 which correspondingly increases or decreases the pressure exerted by sleeve 54 on the dielectric layer 51, and in the range of the minimum capacity settings causes a tapered air gap 60 to form between the electrode 52 and the dielectric layer 51.

The condenser is mounted on a suitable base, for example, a metal chassis 56, by means of a bracket 57 which as shown may consist of an extension of the flap 53 and is provided with two right angle bends. The bracket 57 is secured to the base 56 by means of a rivet 63.

Outside electrical connection to electrode 50 is established through the metal chassis 56 and to the inner electrode 50 through a terminal lug 61 which is secured to its end-face by means of a rivet 62.

In Fig. 5 the invention is shown as applied to a dual unit assembly consisting of a fixed condenser 70 and of an adjustable condenser 71.

The condensers 70 and 71 have a common inner electrode which consists of a hollow metal cylinder or sleeve 72 closed at one end and provided on its surface with an integral coating or layer 73 of a vitreous dielectric material such as described in connection with the condensers of Figs. 1 to 4.

The fixed capacity condenser 70 comprises a wrap-around metal clamp 74, having a cylindrical or sleeve portion 77 forming the outer electrode which surrounds the electrode 72 and is in contact with the dielectric layer 73. The sleeve 77 extends into flaps 75 and 76 which are held together by the rivet 78 which also secures a terminal lug 79 serving as outside electrical connection for electrode 74.

The adjustable condenser 71 comprises a wrap-around metal clamp 80 having a flat strip portion 81, two cylindrical sleeves 82 and 83 forming the outer electrodes and being independent of each other but integral with strip 81. The sleeves 82 and 83 surround the inner electrode 72 and extend into flaps 84 and 85 respectively. The sleeve 83 is pressed, with constant high pressure, into intimate contact with the dielectric 73 by means of a rivet 86 which passes through and clamps together the flap 85 and the strip 81, thereby holding the sleeve clamp 83 rigidly in position on the coated electrode 72-73.

The sleeve 82 is adjustably secured about the electrode 72 by a bolt 87 which passes through the flap 84 and threadedly engages the strip 81. Tightening or loosening of the bolt 87 changes the capacity of the condenser in a manner described in connection with sleeve 15 of the condenser of Figs. 1 to 2. Outside electrical connection for electrode 80 is provided by a terminal lug 88, secured to the strip 81 by the rivet 86.

The closed end of electrode 70 is provided with an axial tapped bore for receiving a suitable mounting bolt, by means of which the condenser assembly can be mounted on a suitable preferably metal base which in practice also serves for electrical connection to the electrode.

While the invention has been described so far, in connection with condensers having a single function, for example, serving as "padder" or tuning condensers, the novel construction of the invention is particularly adapted for imparting to such condensers compensating characteristics. This I achieve, by making the inner and the outer electrodes of the condenser of different

metals of such characteristics, that with increasing temperatures the outer electrode expands radially to a greater or lesser extent than does the inner electrode. Such differential expansion of the two electrodes, causes the outer electrode to exert a greater or a lesser pressure on the dielectric layer or to form a lesser or greater air gap between these two elements thereby correspondingly varying the capacity of the condenser. As a rule, increasing temperatures so change the constants of the tuned circuits of radio receivers as to cause the resonant frequency of the circuit to decrease, in which case I impart to the condenser a negative temperature coefficient of capacity by making the outer sleeve electrode of a metal having a greater temperature coefficient of linear expansion than has the metal of the inner electrode. For example, I make the outer clamp-around electrode of brass and the inner electrode of iron.

A condenser capable of performing simultaneously as tuning condenser and compensating condenser is shown in Fig. 6. The condenser as shown, comprises an inner electrode 100 consisting of a hollow metal cylinder, and a dielectric layer 101 of a vitreous dielectric material which forms an integral coating on the electrode 100. The outer electrode of the condenser consists of sleeve portions of a wrap-around metal clamp which, in this instance, are made up of two separate but mechanically and electrically interconnected members 102 and 103. Members 102 and 103 comprise spaced annular portions 115 and 116 respectively, which form the outer electrodes and surround the electrode 100. The portions 115 and 116 are provided at their two ends with flaps 108-109 and 105-106 respectively. The member 103 is fixedly held about the coated electrode 100 and in contact with the dielectric layer 101 by means of a rivet 104 passing through and securing together the flaps 105 and 106. The member 102 is secured about the coated electrode 100 by means of an adjustable bolt 107 passing through the flap 108 and threadingly engaging the flap 109.

The members 102 and 103 are interconnected by a metal strap 112 secured by rivets 110 and 111 passing through the flaps 106 and 108 respectively.

A terminal lug 120 secured to the flap 108 by rivet 111 serves for the outside electrical connection of the outer electrodes, whereas for such connection of electrode 100 there is provided a lug 121 secured to its end-face, by a rivet 122.

To impart to the condenser the dual function of tuning and compensating condenser, one or both of the members 102 and 103 are made of a metal having a different temperature coefficient of linear expansion than the metal of electrode 100. Such embodiment of the invention lends itself to various combinations of compensating condensers.

For example, by making the fixedly positioned member 103 of brass, and the electrode 100 and the adjustable member 102, of iron and steel respectively, I obtain an adjustable tuning condenser having a substantially constant negative temperature coefficient of capacity. Or by making the adjustable member 102 of brass, and the electrode 100 and the member 103 of iron and steel respectively, a combined tuning and compensation condenser is obtained which has a negative coefficient of capacity, changing proportionally to the capacity setting of the condenser.

In Fig. 7 is shown another embodiment of a

combined tuning and compensating condenser. The condenser there shown comprises an inner electrode 130 consisting of a hollow metal cylinder, and a dielectric layer 131 consisting of a vitreous dielectric material and forming an integral coating on the surface of electrode 130. The outer electrode consists of a sleeve portion 133 of a wrap-around metal clamp member 132 which extends into two contacting flaps 134 and 135. The flap 134 extends beyond flap 135 into a mounting bracket 136 by means of which the condenser is secured by a rivet 139 to a suitable, preferably metal base 140. The flaps 134 and 135 are adjustably secured together by means of a bolt 137 which passes through the flap 134 and threadingly engages the flap 135. Interposed between the head of bolt 137 and the flap 134, is a spacing sleeve 138. External electrical connection to electrode 130 is provided by a terminal lug 141 secured to the end of electrode by a rivet 142 whereas connection to the outer electrode is provided through the metal chassis 140.

The compensating action of the condenser is here produced by making the bolt 137 and the spacing sleeve 138 of materials having different coefficients of linear expansion. By so doing, temperature variations cause a differential expansion of these elements resulting in a change in the pressure exerted by the wrap-around member 132 on the dielectric layer 131, causing the air gap between these two elements to correspondingly vary.

To produce a condenser with a negative temperature coefficient of capacity, the bolt 137 is made of a material with a greater temperature coefficient of expansion than the spacing sleeve 138, whereby with increasing temperature, the greater linear expansion of the bolt 137 causes a decrease in the pressure exerted by electrode 132 on the dielectric 131. This can be achieved, for example, by using a sleeve 138 of "Isolantite" and a bolt 137 of brass. The degree of compensation produced in the condenser is determined by the difference in the respective temperature coefficients of the materials of the bolt 137 and the sleeve 138 and the geometrical relationship of these members.

While I have described my invention with reference to specific examples and in specific embodiments, I do not wish to be limited thereto for obvious modifications will occur to those skilled in the art without departing from the spirit and scope of the invention.

What I claim is:

1. An electrical condenser comprising a cylindrical electrode and a dielectric layer forming an integral coating on the surface of said electrode, a wrap-around metal clamp comprising a plurality of interconnected segments forming coaxial electrodes around said coated electrode, one of said segments being fixedly secured about said inner electrode, and another of said segments being adjustably secured about said inner electrode.

2. An adjustable electrical condenser comprising a cylindrical electrode and a dielectric layer forming an integral coating on said electrode, a wrap-around metal clamp comprising a sleeve member serving as a second electrode, said sleeve member coaxially surrounding the coated electrode and contacting said dielectric layer, a first portion of said sleeve fixedly secured in pressure contact with said dielectric layer, and means to adjust the capacity of the condenser comprising a member adapted to vary the con-

tact pressure between a second portion of the sleeve electrode and the dielectric layer.

3. An adjustable condenser comprising a cylindrical electrode and a dielectric layer forming an integral coating on the surface of said electrode, a wrap-around metal clamp comprising a sleeve portion and flaps extending from said sleeve portion, said sleeve portion constituting the second electrode of the condenser and surrounding said coated electrode, said flaps contacting each other with their inner faces and being fixedly secured to each other at one end of their faces and maintaining the corresponding portion of the sleeve in fixed pressure contact with the dielectric layer, said flaps being adjustably secured to each other at the other end of their faces.

4. An electrical condenser assembly comprising a plurality of condenser units comprising a common cylindrical electrode and a dielectric layer forming an integral coating on the surface of said electrode, and individual wrap-around metal clamps each comprising a sleeve member and constituting the second electrodes for each condenser, said sleeve members coaxially surrounding the coated electrode and contacting said dielectric layer, one of said sleeve members comprising a first portion maintained in a fixed pressure contact with said dielectric layer and a second portion in adjustable pressure relationship with said dielectric layer.

5. An adjustable condenser comprising a cylin-

drical electrode and a dielectric layer forming an integral coating on the surface of said electrode, a plurality of wrap-around metal clamps each comprising a sleeve member constituting the second electrode of the condenser, said sleeve members coaxially surrounding the coated electrode and contacting said dielectric layer, one of said sleeve members fixedly maintained in pressure contact with said dielectric layer and a second sleeve member in adjustable pressure relationship with said dielectric layer, a member rigidly securing together said first and second sleeve members, one of said sleeve members consisting of a metal having a different temperature coefficient of linear expansion than the inner electrode.

6. An electrical condenser comprising a cylindrical electrode and a dielectric layer provided on said electrode, a wrap-around metal clamp comprising a sleeve member constituting the second electrode, said sleeve surrounding the coated electrode and contacting said dielectric layer, said sleeve comprising a plurality of interconnected segments provided with extending flaps, means fixedly securing together a first set of flaps and maintaining a first portion of said sleeve in fixed pressure contact with said dielectric layer, and means adjustably securing together a second set of flaps and adapted to vary the contact pressure between a second portion of said sleeve and said dielectric layer.

FRANK W. GODSEY, JR.
